UNITED STATES PATENT OFFICE.

HOWARD PARKER, OF BERLIN, NEW HAMPSHIRE, ASSIGNOR TO BROWN COMPANY, OF PORTLAND, MAINE, A CORPORATION OF MAINE.

APPARATUS FOR HANDLING PULP TUBES OR THE LIKE.

Original application filed March 3, 1923, Serial No. 622,610. Divided and this application filed November 28, 1924. Serial No. 752,577.

This is a division of my application Serial No. 622,610, filed March 3, 1923, for method of and apparatus for handling and drying pulp tubes or the like.

5 In my said application, I have described and claimed an apparatus wherein the articles to be dried, for instance pulp tubes, are automatically delivered to a suitable carrier, or carriers, by means of which they are carried through a drying chamber and, if desired, a sweating chamber; a current of dry air being suitably passed over the tubes so as to absorb the moisture therefrom.

15 The present invention relates, more particularly, to the means for carrying or conveying the tubes, and has as its object to provide means of this sort which is simple in construction and effective and reliable in operation.

20 In the accompanying drawings, wherein I have shown, for illustrative purposes, one embodiment which the present invention may take;

25 Figure 1 is a detail view of the complete conveying mechanism of the drier including the carriers, the carrier drive mechanisms, and the charging and discharging conveyors, the housing of the drier being omitted;

30 Fig. 2 is a side view showing the receiving end of the carriers and the construction of the transfer conveyor employed for charging the carriers;

35 Fig. 3 is a side view of a portion of the discharging end of the carriers;

40 Fig. 4 is a detail view showing the manner in which the carrier chains are supported;

45 Fig. 5 is a detail view of the forward end of one of the drier carriers, with parts in section;

50 Fig. 6 is a rear view of a portion of the discharge end of the drier mechanism and shows the means for driving the conveyor which receives the dried tubes from the drier carriers;

55 Fig. 7 is a view, partly diagrammatic, showing the manner of associating the drive mechanisms at opposite ends of the drier carriers;

60 Fig. 8 is a detail, in transverse section, of the supporting structure for the chain connecting the drive mechanisms;

65 Fig. 9 is a view of a clutch controlling

mechanism associated with the driving means for the receiving conveyor; and

70 Fig. 10 is a side elevation of a switch controlling the receiving conveyor at the discharge end of the drier.

75 As an instance of a use to which the features of the present invention may be applied, reference may be had to the British Patent No. 229,712, dated August 21, 1923, and issued in the name of E. C. R. Marks. Said British patent discloses certain improvements made by me in machine for manufacturing tubes and other hollow bodies 80 from pulp, and wherein is disclosed a tube forming machine for winding a wet web of pulp in successive convolutions onto a mandrel under pressure until a tube of predetermined thickness is built up, a drier, and means for conveying the tubes from the forming machine to the drier. It is to be understood, however, that said patent is referred to by way of illustration only, it being obvious that the various features of 85 construction hereinafter described may be used in other combinations than that recited in said patent.

90 So that the following detailed description may be more readily understood, a brief statement will be here given as to the general construction and operation of the apparatus.

95 When the improved apparatus herein described is employed in connection with a tube forming machine, such as described in said British patent, the tubes may be automatically delivered from the tube forming machine, one by one, to a transfer conveyor A having a pair of spaced chains 10 provided with devices or chucks 11 adapted to engage and hold the mandrels on which the tubes are formed. Each time a new tube is engaged with the transfer conveyor, the latter is moved ahead one step. At the discharge side of the conveyor, there is a drier having a housing (not shown) provided with a drying chamber preceded, if desired, by a sweating chamber. This drier has a plurality of stages one above the other, and each stage has a horizontally disposed carrier B, each of which may comprise a pair of spaced, endless chains 13 carrying between them rollers 14. After a predetermined 100 number of tubes have been delivered to the

transfer conveyor A, so that there is a tube in front of each stage of the drier, the mandrel holding devices 11 are withdrawn and suitable shifting mechanisms, which may be 5 in the form of pivoted arms C, are actuated for delivering the tubes simultaneously, one to each carrier. These carriers are intermittently actuated, being stepped forward automatically each time a tube is delivered 10 thereto, and the rollers on which the tubes are supported are continuously rotated to keep the tubes in proper shape and to expose all portions of the tube to the drying current. At the discharge ends of the drier 15 carriers is a receiving conveyor D which receives tubes simultaneously, one from each carrier, and conveys them down to a suitable point. In the present instance, I have shown the drier as having ten stages and, 20 therefore, ten carriers, but it is to be understood that the number of stages will depend upon the requirements.

Referring now more in detail to the construction of the apparatus, and particularly 25 to that of the carriers, a description of one of which will suffice as the various carriers are of the same construction, the chains 13 of each carrier pass over sprockets 16 and 16' at the forward and rear ends, respectively, of the drier. The rollers 14 have gudgeons 17 which are journalled in members 18 formed integrally with the side plates of the chain links and having arms 19 extending in the direction of the chains. 30 The arms 19 are adapted to engage with extensions 20 of the chain pins. The weight of each roller is thus spread out over a number of links of the carrier chains so that the tendency of the roller supports to 35 tilt in either direction is overcome. The rollers of each carrier are kept rotating by a constantly moving chain 22 engaging a sprocket 23 on the gudgeon 17 at one end of each roller. The chain 22, which travels 40 parallel to the carrier chains, keeps constantly in motion those rollers which are on the upper side of the carrier. Such rotation of the rollers is of advantage in that the tubes are exposed to the action of the 45 drying current as nearly as possible equally on all parts of their surfaces and, also, the more or less plastic material of the wet tubes is prevented from being pressed out of shape by its own weight. At the respective 50 front and rear ends of the drier, each chain 22 passes over sprockets 25 and 26. One of the latter sprockets 26 is keyed to a shaft 27. The shafts 27 are connected in pairs by means of connecting chains 28 55 passing over sprockets 29, one such sprocket being keyed or otherwise fixed onto each shaft 27. For each pair of shafts thus associated, there is provided an electric motor 30 (see Fig. 1) which transmits its power 60 through a suitable train of gearing 31, the

last gear of the train being fixed on the shaft 27. The object of this gearing is to reduce the speed of the chains 22. It will be noted from Fig. 5 that, when in position suspended from the lower run of the chains 70 13, the rollers 14 are not rotated, since the chain 22 is so spaced that it does not engage the sprockets 23.

In practical use, the drier is of considerable length and, therefore, the carrier chains 75 13 are supported in a suitable manner to prevent sagging. In the embodiment illustrated, there are provided rails 40 upon which antifriction rollers 41, carried by the chains, ride when in their tube supporting 80 position and, on their return, each chain rests on a supporting channel 42 (see Fig. 4).

The carrier chains 13 may be driven by a drive mechanism which applies force at only one end of the drier or, as in the embodiment illustrated here, the force may be applied at both ends. The latter is considered more desirable since one drive mechanism will drive the top runs of the carriers, and the other drive mechanism will drive 90 the bottom runs, and the driving force will be distributed. All of these carriers are driven by entirely similar mechanisms and a description of one is illustrative of all. The drive at the charging end of the drier 95 is shown in detail in Fig. 2, and the drive at the discharge end of the drier is shown in detail in Fig. 3. Referring first to the driving mechanism shown in Fig. 2, there is provided a rack 50 which is driven periodically to rotate a pinion 51 on a shaft 52 upon which the sprocket 16 is also mounted. It is seen that all the pinions 51 are engaged by the rack 50 and operate simultaneously upon the upward motion of the rack 100 to move the carrier chains forward. In order to prevent the carrier chains from being moved in the reverse direction on the down stroke of the rack, each pinion 51 is provided with a ratchet wheel 53 which 105 engages with a pawl 54. This reversing tendency in the chains 13 is also prevented by a brake which comprises a drum 55 rigidly fastened to the supporting framework 110 of the driving mechanism, an internal drum 56 within, and a plurality of balls or rollers 57 which, upon any reversing tendency in the shaft 52 and the drum 56 which is keyed thereto, are adapted to be wedged between 115 the cylindrical surface of the inner drum 56 and wedged shaped projections 58 on the internal surface of the drum 55.

The rack 50 is actuated alternately up and down by a pitman 61, which is connected at its upper end to a large gear 62 associated with the source of power. As the gear 62 rotates, it actuates the rack 50 to move the carrier chains 13 forward a distance equal to the center to center distance between the rollers 14, thereby advancing 120 125 130

two more rollers to position to receive a tube.

For the purpose of supplying tubes to the drier, as, for instance, from the tube forming machine, a transfer mechanism of suitable kind may be employed. This transfer mechanism may include the conveyor comprising the pair of chains 10 provided with pairs of aligned mandrel holding chucks 11 spaced at intervals equal to the distance between the drier carriers above described. The transfer conveyor moves upwardly past the supply point at which it receives the tubes one by one from the tube forming machine, for instance, then horizontally at the top, and then downwardly over a pulley 65 in front of the drier carriers and then about a pulley 66 back to the supply point. In Figs. 1 and 2, the discharge side of the conveyor, that is to say, the vertical run thereof in front of the drier, is illustrated. Each pair of chucks is adapted, as described in the above-mentioned British patent, to be automatically engaged with mandrels (upon which tubes have been formed) at the supply point and then the conveyor is moved ahead one step to bring another set of chucks into position to be engaged with the next mandrel delivered to the supply point. Assuming that such a number of tubes have been delivered to the transfer conveyor and the conveyor has been stepped ahead each time a tube is engaged therewith, that there are nine tubes on the discharge run of the conveyor, one tube in front of each of the first nine stages, when the next tube is engaged with the conveyor and the conveyor is moving ahead so as to bring a tube in front of each of the ten stages, the shifting arms C are moved back under the descending tubes where they have a period of rest. After the conveyor has completed its movements, the chucks 11 are automatically withdrawn so as to disengage the mandrels which are now resting on the shifting arms. The shifting arms are then thrown forward so as to deliver the tubes thereon to the respective carriers. The transfer conveyor continues its operation of picking up the mandrels one by one from the supply point until there are nine more tubes in front of the drier, when the series of operations just described are repeated.

Each shifting arm C is provided with a suitably shaped portion 70 for receiving the ends of the mandrels. These arms C are fixed in pairs to the respective shafts 71 and each shaft has at one end an arm 72. Each arm 72 is connected by means of a link 73 to a respective crank 74 carried by a pinion 75 engaging a spur gear 76 on the shaft 52.

In operation, a switch (not shown) is provided which is operated once upon every ten steps forward of the transfer conveyor and

this switch closes the circuit of a solenoid 80 controlling the rotation of the gear 62. As shown in Fig. 2, the solenoid 80 is provided with a bell crank 81 which normally supports or latches in position a bar 82. The purpose of this bar is to maintain a dog 83 out of engagement with a ratchet provided in a clutch 84. When the solenoid 80 is energized, as before described, it releases the bar 82, permitting the dog 83 to engage the clutch 84 and thereupon power is transmitted through the reduction gearing 85, 86, to the gear 62 which is thereupon actuated to move the rack 50. The gear 62 then rotates counterclockwise, somewhat less than 180°, until the crank pin 88 is positioned horizontally with respect to the shaft 89 upon which the gear 62 is journalled. At this position, the bar 82 is actuated by means of rollers 90 which strike against an extension 91 of the bar 82 to raise the dog 83, thereby releasing the clutch 84.

During this partial rotation of the gear 62, the rack is first lowered turning the pinions or gears 51 clockwise without actuating the carrier mechanism, and then the rack is raised during which time the drier carriers are moved forwardly a portion of a step and the arms C are thrown back into position beneath the now descending tubes carried by the transfer conveyor. The drive mechanism including the gear 62 now remains momentarily at rest until the descending tubes are brought into position on the arms and the chucks 11 are withdrawn. As the arms C move backwardly to this position, one of such arms carries back with it a switch 93 (Fig. 1) by means of an arm 94 keyed to one of the shafts 71 supporting the shifting arms C. This switch 93 is positioned at one side of one of the transfer conveyor chains 10 and is actuated by contact with a chuck head 11 descending thereon. Switch 93 is adapted to close a circuit including a solenoid 95 which, as described in the above-mentioned British Patent No. 229,712, operates to engage a clutch (not shown) which is located in the train of gears (not shown) operating the chuck releasing mechanism (not shown). Thereupon, all the chucks 11 in front of the carriers B are released and held in such position, permitting the mandrels to drop into the receiving ends 70 of the arms C. When the chuck releasing mechanism is thus actuated, a suitable switch 96 associated therewith closes the circuit of the solenoid 80 whereupon clutch 84 is again engaged to rotate the gear 62 through the remaining portion of one revolution. As the gear is thus rotated, the rack is raised causing each of the drier carriers to complete its step motion, and also moving the shifting arms C forwardly so that the tubes carried thereby will roll down the same onto the rollers of the drier.

carriers which are brought into receiving position when the arms have been moved to their forward delivering position. When the gear 62 has completed its revolution, the 5 bar 82 is again engaged by one of the rollers 90 to disengage the clutch 84. Two rollers 90 are mounted upon each of a pair of small gears 98 which are in turn supported upon the shaft 89. The gears 98 are actuated by 10 a stationary pinion 99 so that upon rotation of the gear 62 the gears 98 also rotate, giving the rollers 90 a planetary motion of their own. There are two such sets of rollers 90 with similar actuating mechanism, and they 15 are placed somewhat less than 180° apart. As they pass by the extension 91 of the bar 82, they are adapted to strike thereagainst to stop the motion of the gear 62 by disengaging the clutch 84. Subsequently, upon 20 energization of the solenoid 80, the clutch 84 is again engaged causing the gear 62 to rotate and return the pitman to its position, as shown in Fig. 2.

As has been above described, there are two 25 rollers 90 on each gear 98. The purpose of having two rollers 90 is to provide a means for varying the distance the carriers are advanced. The gear ratio between the gears 98 and the pinion 99 is such that these rollers 30 90 will alternately contact against the extension 91 of the bar 82 so that if one of the rollers 90 be removed from each gear 98, the remaining rollers 90 will strike against the extension 91 only upon the alternate 35 revolutions of the gear 62. In such case, the rack 50 is reciprocated twice instead of once, as before described, and the conveyor is moved forward two steps. As a general 40 proposition, this is desirable in case the tubes delivered to the conveyor are of a diameter greater than the center to center distance between the rollers 14.

At the discharging end of the drier, the 45 driving mechanism is substantially the same as at the charging end described, except that the shaft 52' carries a sprocket 105 which is associated with the main driving shaft 106 by means of a chain 107, and a sprocket 108 on the shaft 106. Shaft 106 is driven in 50 precisely the same manner as the shaft 52, there being provided a rack 50', pinion 51', and the brake previously described. The sprocket 108 is so constructed that its periphery may be rotated with respect to the 55 shaft 106, there being provided dogs 109 carried by an internal section 110 rigidly attached to the shaft 106, and teeth on the internal edge of the outer section of the sprocket for engagement with dogs 109. In 60 the internal section 110, there are provided circular apertures 111 into which may be inserted a round tool (not shown) with teeth to engage the teeth on the internal surface of the exterior portion of the sprocket. 65 When this tool is inserted into the aperture

111 and rotated in a counterclockwise direction, the exterior portion of the sprocket is rotated with respect to the inner section 110 to take up the slack in the chain 107. This arrangement provides means for angularly 70 adjusting the sprocket 16' relative to the corresponding sprocket 16 at the other end of the drier so that the teeth of both of these sprockets will properly mesh with the chains 13 and each will assume its proportionate 75 share of its driving duty. Thus, the driving force applied to the chains 13 is equally distributed to the driving mechanisms at the opposite ends of the drier.

Slack in the carrier chains 13, due to wear 80 or stretching, may be taken up by means of a bolt 114 provided with a nut 115 and attached at the other end to the bearing of the shaft 52' (Fig. 3). By tightening or 85 loosening the nut 115 the bearing may be moved forward and backward to tighten or loosen the chain, as desired.

The power to operate the gears 62 and 62', which through the respective pitmen 61 and 61' reciprocate the racks 50 and 50', is 90 supplied from a pulley 116 through a chain or belt 117 to a sprocket or pulley 118 mounted on the shaft 119. There are two sprockets provided on shaft 119. One of these sprockets is connected by a chain 120 95 to a sprocket 121 mounted on the same shaft as the clutch 84. The other sprocket is connected by means of a chain 122 to a sprocket 123 on a shaft 124. Another sprocket 125 of the same size as sprocket 123 is mounted 100 on shaft 124 and is associated by means of a chain 126 with a sprocket 127 of equal size mounted on shaft 128 at the discharge end of the drier. A second sprocket 129 on shaft 128 connects by means of a chain 130 105 with a sprocket 131 mounted on the shaft with the clutch 84'. Thus the power from the pulley 116 is transmitted equally to the clutches 84 and 84' and thereby to operate the pitmen 61 and 61'. There are provided 110 suitable adjustable idler sprockets 132, by means of which slackness in the chain 126 may be taken up and adjusted.

The chain 126 is necessarily of great 115 length since it extends from end to end of the drier chamber and, therefore, that portion of the chain which is under tension is kept immersed in a bath of oil contained in a trough 133 (Fig. 8), to reduce friction and wear in the pins and bearings of the chain. 120 There is also provided in the trough 133 a guide comprising a pair of vertically spaced blocks 134 and 135, block 135 being supported on the floor of the trough, and block 134, which is the upper of the two, being bolted to a supporting member 137. The chain 126, which is preferably of the roller type, is held between the members 134 and 135 by its side plates, while the rollers roll 125 with practically no friction between the 130

guides. The weight of the trough 133 and the parts therewithin is borne by suitable structural members such as an I-beam 138. The upper side of chain 126 is supported by idler sprockets 139 spaced at suitable intervals.

There is thus provided a complete physical connection between the two drive mechanisms at the opposite ends of the drier and, therefore, neither mechanism can advance over the other and produce an undue burden on the other mechanism. This arrangement also insures a complete synchronism of the whole system. The solenoids 80 and 80', which control the clutches 84 and 84' to rotate the gears 62 and 62', respectively, are accordingly controlled by the same electrical circuit. Therefore, they operate simultaneously and start and stop the drive at substantially the same instant.

When a tube has reached a position between the last two rollers on the upper side of a carrier B, the next step forward of the carrier will drop the tube into a discharge conveyor D having curved arms 149, one pair of such arms being normally positioned before such carrier. The ten tubes delivered from their respective carriers are thus dropped into these receiving arms 149 simultaneously and, at the same time, a mechanism is set in motion to lower these arms, delivering the tubes carried thereby into a suitable receptacle (not shown) below. The arms 149 are mounted on chains 150 which pass over guiding sprockets 151 above and similar sprockets 152 below. The chains 150 also pass over large sprockets 153 by which the receiving arms 149 are moved in a continuous path into receiving position before the carriers and inverted as they are brought back on the opposite side. The sprockets 153 (Fig. 6) are mounted on a shaft 154 which is also provided with another sprocket 155 connected by a chain 156 with a sprocket 157 mounted on a shaft 158. The power to drive this discharging conveyor D is provided by the same source which drives the crank gear 62' and is applied through a clutch connected with a power driven shaft 160 through suitable sprockets 161 and 162, and a chain 163. A pinion 165 is loosely journalled on a shaft 166 upon which the sprocket 161 and the fixed portion 167 of the clutch are mounted. This pinion, with the clutch engaged, is adapted to drive the gear 170 and the sprocket 157 rotatable therewith, and in consequence the main driving sprockets 153 for the discharging conveyor chains 150. The clutch for this mechanism is shown in detail in Fig. 9 and comprises the portion 167 fixed to the shaft 166, a disk 171 integral with the pinion 165 and normally rotatable on the shaft 166, and a controlling disk 172 which is adapted to hold the clutch engaged for the interval of time required for the chains 169

to be stepped forward a distance sufficient to discharge all of the receiving arms 149. The clutch (Fig. 9) is controlled by a pivoted forked member 173 having forwardly extending arms 174 and 175. Engagement between the fixed portion 167 and the disk 171 is made by a dog 176 which is adapted to move in a direction radial of the disk 171, in a slot 177 in the disk. The dog is substantially rectangular in cross section and extends inwardly and under the fixed portion 167 so that upon its movement radially outward it may slide into position in rectangular notches 178 provided in the edge of the fixed member 167 adjacent the disk 171. It will be seen that upon the insertion of the dog 176 in any one of the notches 178, the two members 167 and 171 are keyed together and, in such case, the power from the shaft 160 is transmitted to the receiver arm carrying chains 150 through the gearing and chains above described. The radial movement of the dog 176 is controlled by a bell crank which has a short arm 179 engaging the dog 176 in a notch 180 thereof; and a relatively long arm 181 which extends slightly beyond the periphery of the disk 171 so as to be engageable by the arm 174. A sector of the disk 171 is cut away at 182 to provide room for the rotation of the bell crank, and, more particularly, its arm 181. Beneath the dog 176 there is mounted a spiral spring which normally presses the dog upwardly. Thus, when released, the arm 181 of the bell crank tends to move to position against the edge of the sector 182.

A solenoid 185 is provided to lift the pivoted member 173 so that its arm 174 disengages from the arm 181 permitting the clutch to take hold and transmit the desired power. The solenoid 185 is operated upon the closing of its circuit by a switch controlled by the rotation of the gear 62'. This switch, which is shown in detail in Fig. 10, comprises a commutator 186 having three electrically conductive bars 187 spaced from each other by the body of the commutator which is preferably of a hard insulating material. The commutator 186 is rotatably mounted on a bracket 188 and is rotated by means of a star wheel 189 having six arms, each alternate arm corresponding to a segment 187. Two bars 190 are pivotally mounted on the bracket 188 and are pressed against the commutator 186 by means of coil springs 191. Each of these bars has a contact 192 with a lug 193 thereon for attachment with an electrical conductor. The electrical circuit of the solenoid 185 is therefore closed whenever the commutator bars 187 contact with the contacts 192. At all other times, this circuit is open. This closure is accomplished by a pin 194 on the edge of gear 62' which turns the star wheel 189 in passing. The circuit is again opened by further rotation of the 189

star wheel turned by a second pin 195 on the gear 62'. Thus the solenoid 185 remains energized for a short period of time allowing the mechanism time to get under way before leaving it entirely to its own automatic stop device. This energization of the solenoid is only momentary and therefore additional means is provided to keep the pivoted member 173 elevated so that upon rotation of the disk 171 the arm 181 will not be tripped by the arm 174 until all ten of the receiver arms 149 have deposited their tubes, as above described. This means for maintaining the pivoted member 173 in elevated position includes the disk 172 and the arm 175.

On the shaft 154 which supports the sprocket 153, there is fixed a smaller sprocket 198 which is connected by a chain 199 with a sprocket 200 loosely journalled on the shaft 166. The sprocket 200 is formed integrally with the disk 172. It will be seen, therefore, that upon movement of the arms 149 with the chains 150, the disk 172 is rotated by means of the sprockets 200 and 198 in such a manner that the bent arm 175 is held up to keep the clutch disengaged. Re-engagement of the clutch cannot take place until the disk 172 has rotated a complete turn to permit the arm 175 to fall into the notch 178 whereupon the arm 174 can again engage the arm 181 to release the clutch mechanism. The rotation of the disk 172 is accordingly timed by proportioning the sprockets 200 and 198 so that there is one revolution of the disk 172 upon ten steps forward of the arms 149.

The operation of the drive mechanism is as follows: When the transfer conveyor chains 10 have advanced nine and a fraction steps so that a tube carried by one of the chucks is approaching a position in front of the lower-most carrier B, the solenoids 80 and 80' located at the opposite ends, respectively, of the drier, operate and engage the clutches 84 and 84' to start the gears 62 and 62' to rotate. Thereupon, by means of the pitmen 61 and 61', the racks 50 and 50' are reciprocated and upon the upstroke, the pinions 51, 51' are rotated thereby in a counterclockwise direction. By means of the connecting rods or links 73, the shifting arms C are caused to tilt backwardly under the approaching tubes. This causes the receiving ends 70 of the shifting arms C to assume the position shown in dotted lines, Fig. 2, beneath the tubes. The chains 13 are simultaneously advanced carrying the rollers 14 forward slightly. The gear 62 stops with the crank pin at a substantially horizontal position as one of the small rollers 90 engages the extension 91 of the bar 82 thereby disengaging the dog 83 of the clutch 84. Meanwhile, the chains 10 of the transfer mechanism are advanced so that the tubes 65 now rest within the receiving ends 70 of the

shifting arms C, at which point the entire mechanism stops momentarily. Also, the switch 93 has moved forward with the shifting arms C so that the head of one of the chucks 11 rests thereon closing the switch 70 contacts to complete the circuit of the solenoid 95 which operates to close the clutch connecting a suitable source of power with the chuck disengaging mechanism. With the tubes thus disengaged, the solenoids 80 and 80' again operate, engaging the clutches 84 and again starting the rotation of the gears 62 and 62', whereupon the racks 50 and 50' cause the chains 13 to advance the rollers 14 to position to receive tubes therebetween, and additionally the shifting arms C are caused to move forward until they tilt slightly, whereupon the tubes roll from the receiving ends 70 into position between the rollers 14. At the discharge end of the drier, the circuit of the solenoid 185 has, meanwhile, been completed, raising the forked member 173 and engaging the clutch associated therewith. Power is then transmitted to the pinion 165 through this clutch 90 to rotate the gear or sprocket 155 causing the chains 150 to carry downwardly the tubes discharged into the curved arms 149, depositing them either on the floor or in a suitable receptacle. 95

Thus, by the above construction, are accomplished, among others, the objects hereinbefore referred to.

As many changes could be made in the above construction and many apparently widely differing embodiments of this invention could be made without departing from the scope thereof, it is intended that all matter contained in the above description or shown in the accompanying drawings shall 100 be interpreted as illustrative and not in a limiting sense. 105

It is to be understood that the language used in the following claims is intended to cover all of the generic and specific features 110 of the invention herein described, and all statements of the scope of the invention which, as a matter of language, might be said to fall therebetween.

I claim as my invention: 115

1. In an apparatus of the character described, a carrier having a pair of endless chains, pairs of aligned members each carried by one link of a chain and having extensions overlying a number of links of the chain, and rollers journalled in said members. 120

2. In an apparatus of the character described, a pair of spaced endless chains, article supporting members carried by said chains, sprockets at the opposite ends of said carrier over which said chains pass, means for driving the sprockets at each end of said carrier, and means for angularly adjusting the sprockets at one end relative to those at 125 130

the other end, and including a pair of rotatable members one positioned about the other, and means for locking the members in any position of adjustment.

3. In combination, a drier, a carrier within the drier and having transversely extending supporting rollers, means to deliver articles singly to between the rollers of the carrier, a drive mechanism driven in timed relation to said delivery means to advance said carrier intermittently upon delivery of such articles to the carrier, and a control mechanism to vary the distance said carrier is advanced at each such delivery.

4. In combination, a carrier, means to deliver articles singly to the carrier, a drive mechanism including a rotary member to advance said carrier intermittently upon delivery of an article thereto, and a control mechanism to vary the number of advances made by the carrier at each delivery of articles thereto, said control mechanism comprising a clutch and means interposed between said clutch and said rotary member to engage and disengage said clutch.

5. In combination, a carrier, means to deliver articles singly to the carrier, a drive mechanism including a rotary member to advance said carrier intermittently upon delivery of an article thereto, and a control mechanism to vary the number of advances made by the carrier at each delivery of articles thereto, said control mechanism comprising a clutch, a controlling lever for said clutch, and members rotatable with said rotary member to actuate said lever, certain of the last said rotatable members being removable.

6. In an apparatus of the character described, an endless carrier, a drive mechanism at each end of said carrier, a continuously driven chain connecting said driving mechanisms, and automatically operated means associated with each mechanism and operable in unison for connecting and disconnecting said drive mechanisms with said chain.

7. In an apparatus of the character described, a carrier comprising a pair of chains and transversely extending rollers supported thereby, a pair of reciprocating arms at the forward end of the carrier adapted to move away from the carrier to receive an article and then advance towards the carrier to deliver an article thereto, said arms having roller supporting portions down which the articles roll by gravity when the arms are in delivery position, and means for intermittently driving the carrier and operating said arms.

8. In an apparatus of the character described, a carrier, a pair of shifting arms at the forward end of said carrier, means for moving the carrier forward a portion of a step and simultaneously moving the arms backwardly, and then completing the step

movement of the carrier and moving the arms forwardly.

9. In an apparatus of the character described, a plurality of superposed endless carriers, a driving sprocket at the end of each carrier, means for driving said sprockets, means for independently and angularly adjusting one of the driving sprockets of each carrier, and means for driving said sprockets in unison.

10. In an apparatus of the character described, a plurality of superposed endless carriers and a drive mechanism common to said carriers, and including a pinion associated with each carrier, a rack common to said pinions, and means for reciprocating the rack.

11. In an apparatus of the character described, a plurality of superposed endless carriers, and a drive mechanism common to all of said carriers and including a pinion for each carrier, a ratchet and pawl connection between each carrier and its pinion, a rack common to said pinions, and means for intermittently reciprocating said rack.

12. In an apparatus of the character described, a plurality of superposed carriers, a drive mechanism at each end of and common to all of said carriers, and means for operating both of said driving mechanisms in synchronism.

13. In an apparatus of the character described, a drying chamber, a plurality of superposed endless carriers therein, a drive mechanism at each end of said carriers, controlling means for said driving mechanism operable in unison, and a chain connecting said drive mechanism.

14. In an apparatus of the character described, a plurality of superposed carriers, means in front of each carrier for delivering articles thereto, and means for simultaneously actuating said means.

15. In an apparatus of the character described, a plurality of superposed carriers, a shifting arm mounted for reciprocation in front of each carrier and adapted to deliver articles thereto, means simultaneously operating said shifting arms, and means for moving said carriers intermittently.

16. In an apparatus of the character described, a shifting arm mounted for reciprocation in front of each carrier and adapted to deliver articles thereto, and means to operate said shifting arms simultaneously and to advance said carriers a step, said means including a pinion for each carrier and its associated shifting arm, and a power driven rack common to all of said pinions.

17. In an apparatus of the character described, a plurality of superposed carriers, a drive mechanism to step said carriers forwardly, and means in front of each carrier and operable in unison to deliver tubes simultaneously one to each other.

18. In an apparatus of the character described, a plurality of superposed carriers, a drive mechanism for said carriers, means at the receiving ends of the carriers for simultaneously delivering articles one to each carrier, and means for simultaneously receiving the articles one from each carrier.
19. In an apparatus of the character described, a plurality of superposed carriers, driving means therefor, means at the receiving ends of the carriers for simultaneously delivering articles one to each carrier, means at the discharge end of the carriers for simultaneously receiving articles one from each carrier, and a system of control for all of said means.
20. In an apparatus of the character described, a plurality of superposed carriers, means for intermittently driving the same, a conveyor having a vertical run disposed at the discharge ends of said carriers and adapted to simultaneously receive tubes one from each carrier, and means for intermittently driving said conveyor.
21. In an apparatus of the character described, a plurality of superposed carriers, drive mechanism for said carriers, and means controlled by said drive mechanism for simultaneously receiving articles one from each carrier.
22. In an apparatus of the character described, a plurality of superposed carriers, drive mechanism for said carriers, and a discharge conveyor controlled by said drive mechanism and adapted to simultaneously receive articles one from each carrier.
23. In an apparatus of the character described, a plurality of superposed carriers, means for intermittently driving the same, a conveyor having a vertical run disposed at the discharge ends of said carriers and adapted to simultaneously receive tubes one from each carrier, and means for intermittently driving said conveyor, said last men-
- tioned means being controlled by the operation of said carriers.
24. In an apparatus of the character described, a plurality of superposed carriers, means for intermittently driving the same in unison, a conveyor having a vertical run disposed at the discharge ends of said carriers and adapted to simultaneously receive articles one from each carrier, means for intermittently driving said conveyor each time tubes are delivered thereto, and a system of control through which said driving means for said carriers control said driving means for said conveyor.
25. In an apparatus of the character described, a plurality of superposed carriers, a drive mechanism therefor, a receiving conveyor at the discharge end of said carriers and adapted to receive articles therefrom, an electro-magnetically operated clutch associated with said conveyor for driving the same, and an electric switch operable by said drive mechanism and controlling said clutch.
26. In an apparatus of the character described, a plurality of superposed carriers, a drive mechanism for said carriers including an intermittently rotatable member, an endless conveyor disposed at the discharge end of said carriers and adapted to receive articles simultaneously one from each carrier, an electro-magnetically operated clutch associated with said conveyor for driving the same, and an electric switch operable by said drive mechanism to control said clutch, said intermittently rotatable member having means thereon for actuating said switch to energize the magnetically operated member, and other means on said intermittently rotatable member for actuating the switch to break the circuit through the magnetically operated member.

HOWARD PARKER.
